(57) **CLAIM**

The ornamental design for a USB drive holder, as shown and described.

DESCRIPTION

FIG. 1 is a side, top, perspective view of the USB drive holder shown in the spine of a notebook illustrated in broken lines; FIG. 2 is a left side view thereof;

FIG. 3 is a right side view thereof;

FIG. 4 is a rear view thereof;

FIG. 5 is a front view thereof;

FIG. 6 is a top view thereof;

FIG. 7 is a bottom view thereof;

FIG. 8 is a perspective front view thereof with the notebook shown opened;

FIG. 9 is a cutaway perspective rear view thereof with a USB drive shown separately;

FIG. 10 is a cutaway perspective front view thereof; and,

FIG. 11 is a cutaway perspective top view thereof.

The broken lines shown are included for illustrative purposes only form no part of the claimed design.
